UNITED STATES PATENT OFFICE.

JOSEPH L. O'BRIEN, OF NEW YORK, N. Y.

DESIGN FOR FRINGE.

SPECIFICATION forming part of Design No. 13,632, dated February 20, 1883.

Application filed January 19, 1883. Term of patent 3½ years.

To all whom it may concern:

Be it known that I, JOSEPH L. O'BRIEN, of the city, county, and State of New York, have invented a new and Improved Design for Fringe, of which the following is a full, clear, and exact description.

Reference is to be had to the accompanying drawings, forming part of this specification, in which a piece of my newly-designed fringe is shown.

From a heading, A, a series of elliptical blocks, B, are suspended, which blocks are provided at the top and bottom with tufts C. The lower tufts of the several blocks B are united by cords or strands D, and to the said strands tassels E or other suitable pendants are attached, the said tassels or pendants hanging from the said cords or strands. The heading A may be of any desired pattern. The blocks B are made of wood or paper, and are overspun with silk. They may be smooth or fluted spirally or longitudinally, and the tufts C may be of any desired pattern, design, or color. The style and design of the pendants E can be varied, as may be desired, as the essential feature of my newly-designed fringe consists in the blocks B, which are placed at or near the middle of the fringe.

Having thus described my invention, I claim as new and desire to secure by Letters Patent—

1. The design for fringe herein shown and described, consisting of the elliptical blocks B, held vertically at about the middle of the fringe, as set forth. 35

2. The design for fringe herein shown and described, consisting of elliptical blocks provided at the top and bottom with tufts, and held at about the middle of the fringe, as set forth. 40

3. The design for fringe herein shown and described, consisting of elliptical blocks having tufts at the top and bottom, the bottom tufts being united, and pendants being suspended from the cords uniting the said tufts, 45 as set forth.

4. The design for fringe herein shown and described, consisting of elliptical blocks B, provided with tufts at the top and bottom, which blocks are suspended from a heading, 50 A, and have pendants suspended from their lower ends, as set forth.

JOSEPH L. O'BRIEN.
